(57) CLAIM

(21) Appl. No.: 29/155,863

The ornamental design for a deck boat seating arrangement, as shown and described.

(22) Filed: Feb. 21, 2002

DESCRIPTION

(62) Division of application No. 29/127,684, filed on Aug. 9, 2000.

FIG. 1 is a perspective illustration, from the rear and left side, of the deck boat seating arrangement of our design; FIG. 2 is a perspective illustration thereof, from the front and left side; and,

(51) LOC (7) Cl. 12-06

FIG. 3 is a top view thereof.

(52) U.S. Cl. D12/300

Where included, broken lines showing environment or structure are for illustrative purposes only and form no part of the claimed design.

(58) Field of Search D12/300-318; 114/270, 271, 355.5, 355.57, 355.54

The omission of a view indicates that the omitted view is plain and unornamented.
